CLAIM

The ornamental design for a holder for ties and accessories, as shown and described.

DESCRIPTION

FIG. 1 is a front elevational view of a holder for ties and accessories in an unfolded configuration;

FIG. 2 is a front right top perspective view of FIG. 1 in a folded configuration;

FIG. 3 is a front right top perspective view of FIG. 1 in a folded configuration and in environmental use;

FIG. 4 is a front elevational view of FIG. 2;

FIG. 5 is a rear elevational view thereof;

FIG. 6 is a right side elevational view thereof;

FIG. 7 is a left side elevational view thereof;

FIG. 8 is a top plan view thereof;

FIG. 9 is a bottom plan view thereof;

FIG. 10 is a front elevational view of a second embodiment of the holder for ties and accessories in an unfolded configuration;

FIG. 11 is a front right top perspective view of FIG. 10 in a folded configuration;

FIG. 12 is a front right top perspective view of FIG. 10 in a folded configuration and in environmental use;

FIG. 13 is a front elevational view of FIG. 11;

FIG. 14 is a rear elevational view thereof;

FIG. 15 is a right side elevational view thereof;

FIG. 16 is a left side elevational view thereof;

FIG. 17 is a top plan view thereof; and,

FIG. 18 is a bottom plan view thereof.

The dot-dash broken lines shown in the figures represent environmental subject matter and form no part of the claimed design.
